UNITED STATES PATENT OFFICE

JOHN COSTELLO, OF PHILADELPHIA, PENNSYLVANIA; ANNIE COSTELLO AND WILLIAM COSTELLO EXECUTORS OF SAID JOHN COSTELLO, DECEASED

BIT FOR TAPER BORING

Application filed November 12, 1924. Serial No. 749,368.

My invention relates to an improvement in pack bits and more particularly to a bit for taper boring.

The object of my invention is to provide a bit by means of which a bore may be tapered with great accuracy.

Further objects of my invention are to provide a bit of the character indicated, which will be of simple construction and at the same time efficient and durable in operation.

Having now indicated, in a general way, the nature and purpose of my invention, I will proceed to a detailed description thereof, with reference to the accompanying drawings in which I have illustrated a preferred embodiment thereof, and in which,

Fig. 1 is a plan view of a bit embodying my invention.

Fig. 2 is a side elevation of the bit shown in Figure 1.

Fig. 3 is a side view of a portion of the feed rod.

Fig. 4 is an enlarged end view of the bit shown in Figures 1 and 2.

Fig. 5 is a side view, partly broken away, of the subject of Figure 4.

Fig. 6 is an elevation of a boring bar bearing showing feed rod drive.

Fig. 7 is a side view of the subject of Fig. 6, partly in section.

a represents the body of a pack bit having at its rear a shank *b* provided with a cross key slot *c*, for connection with a boring bar *d*, and a shank *e* at its forward end, for connection with a pilot.

Spaced back from the forward end and adjacent one side, the body is drilled transversely of its axis, as at *f*, and is slotted, parallel to the axis, as at *g*, to form an arm *h*, adjacent the free end of which provision is made for the reception of a cutting tool *i* adapted to be adjustably secured by means of bolts *j*. Similar provision is made for adjustably securing a cutting tool *k* to the body opposite to the tool *i*, though the use of a second tool, as *k*, is not necessary.

An undercut groove *l* is cut in the body parallel to the slot *g* and a similar groove *l'*, extending at an angle to the slot *g*, is cut in the arm *h*, so that the slot *l'* in its extension

from the forward end of the arm *h* diverges from the slot *l* and form guides on the body portion and arm *h*. The adjacent walls of the slots *l* and *l'* are finished to provide bearings for projections on a slide *m*, which projections are adapted to bear at their forward and rear ends in the slot *l* and at their forward end only, in the slot *l'*, as shown in Fig. 5 while the body portion embraces the guides.

Carried by the slide is a nut or internally threaded portion *n*, adapted for the reception of the threaded end of a rod *o*, adapted to be connected for rotation, as at *p*, to a feed rod *q*. The rod *o* is prevented from endwise movement relative to the body *a* of the bit by means of the engagement of collars *r* on opposite sides of a bearing *s* secured to the body of the bit.

It will now be observed that if the slide *m* be moved toward the rear of the bit the free end of arm *h* will be moved toward the axis of the body, due to the divergence of the slots *l* and *l'*, and the depth of cut of the tool *i* will be reduced. If the slide is thus moved as the bit is advanced in a bore, the tool *i* will produce a tapered bore.

For the purpose of moving the slide *m* during the advance of the bit, which may be accomplished by rotation of the threaded end of rod *o* in nut *n*, feed rod *q* is provided with a helical groove *t*, adapted to be entered by a key *u* adapted to be secured to a quadrant *v*, adjustably secured on the rear face of the boring bar bearing, of a boring machine of usual construction.

The quadrant *v* is provided with an arcuate slot *w* through which are adapted to pass bolts *x* for securing the quadrant, in adjusted position, to the boring bar bearing and the quadrant is provided with a plurality of spaced slots *y* for the reception of the key *u*, which is adapted to be secured to the quadrant by a screw *z*, in order that by adjustment of the quadrant itself and selection of a slot the key may be entered in the groove of the feed rod *q* without turning the feed rod.

In operation, as the bit is advanced relative to the rotating work, it will be observed that the feed rod will be turned by the en-

gagement of the fixed key in the helical groove in the rod, with the result that the threaded end of rod *o*, which is prevented from endwise movement, will advance through nut *n* and act to move slide *m*. Movement of slide *m* will cause the arm *h* to be drawn in, thus gradually reducing the depth of cut of tool *i* with the production of a tapered bore. It will be noted that the arm *h* is possessed of resiliency and when drawn in by the slide tends to spring out to normal position, thus setting up an opposing force to that of the slide, which tends to retain the arm in any position into which it is drawn and enables it to be drawn in with great accuracy.

It will be understood that if a second tool, as tool *k*, is used, such tool will be adjusted initially to cut on a diameter equal to the minimum diameter of the tapered bore to be produced, while the tool *i* will be initially adjusted to cut on a diameter equal to the maximum diameter of the tapered bore to be produced.

It will be obvious that any desired taper within predetermined limits may be produced by relatively proportioning the degree of divergence of the slots *l* and *l'* and the travel of slide *m*, to the length of the bore to be produced, but more simply by varying the pitch of the helical groove cut in rod *q* so that in conjunction with the thread in nut *n* it will move slide *m* and tool *i* at the proper rate.

It is obvious that the rod *q* may be rotated by a cam, or by gears or in any convenient way, and I do not confine myself to the spline shaft method illustrated.

Having now fully described my invention, what I claim and desire to protect by Letters Patent is:

1. A bit for taper boring comprising a body portion, an arm formed integral with the body, and extending longitudinally of, said body, a cutting tool secured adjacent the free end of said arm, means engaging said body and arm and adapted to be continuously actuated in the operation of the body to move the free end of the arm toward the axis of said body.

2. A bit for taper boring comprising a body portion, an arm formed in, and extending longitudinally of and having one of its ends fixed relative to said body, a cutting tool secured adjacent the free end of said arm, a guide on said body and extending parallel to the axis thereof, a guide on said arm extending at an angle to the axis of said body, a slide embracing said guide, and means to move said slide to cause the free end of said arm to be drawn toward the axis of said body.

3. A bit comprising a body portion slotted longitudinally from its forward end to form

an arm an end of which is fixed relative to said body, a cutting tool secured adjacent the free end of said arm, a groove in said body extending parallel to the axis thereof, a groove in said arm extending at an angle to said first mentioned groove, a slide engaged in said grooves, a nut carried by said slide, a screw engaging said nut, means to prevent endwise movement of said screw relative to said body, and means to rotate said screw.

4. A bit comprising a body portion slotted longitudinally from its forward end to form an arm, a cutting tool secured adjacent the free end of said arm, a groove in said body extending parallel to the axis thereof, a groove in said arm extending at an angle to said first mentioned groove, a slide in said grooves, a nut carried by said slide, a screw engaging said nut, means to prevent endwise movement of said screw relative to said body, a helically grooved feed rod connected to said screw, a boring bar connected to said body, a fixed key entered in the groove in said rod and adapted as the bit is advanced by said boring bar to rotate said feed rod.

5. A bit comprising a body portion slotted longitudinally from its forward end to form an arm, a cutting tool secured adjacent the free end of said arm, a groove in said body extending parallel to the axis thereof, a groove in said arm extending at an angle to said first mentioned groove, a slide in said grooves, a nut carried by said slide, a screw engaging said nut, means to prevent endwise movement of said screw relative to said body, a helically grooved feed rod connected to said screw, a boring bar connected to said body, a fixed support for said feed rod and boring bar, a quadrant adjustably secured to said support, a plurality of slots in said quadrant for alignment with the groove in said feed rod, a key adapted to be entered in the groove in said feed rod and in an aligning slot in said quadrant, and means to secure said key to said quadrant.

6. A bit for taper boring comprising a body portion, an arm extending longitudinally of said body and formed integrally therewith adjacent one end, a cutting tool secured to said arm, means to move the free end of said arm toward the axis of the body and resilient means for resisting the movement of the free end of the arm toward said axis.

7. A bit for taper boring comprising a body portion, an arm secured at one end to, and extending longitudinally of, said body, a cutting tool secured adjacent the free end of said arm, a groove formed in the body, a groove formed in said arm, one of said grooves extending at an angle to the other, a slide extending from groove to groove and embracing guides formed between said grooves, and means to move said slide to cause the free end of said arm to be drawn toward the axis of said body.

8. A bit for taper boring comprising a body portion, an arm formed integral therewith and extending longitudinally a portion of said body, a tool secured to said arm adjacent its free end and means continuously and positively actuated by the forward movement of said bit adapted to move the free end of said arm toward the axis of said body.
9. A bit for taper boring comprising a body portion, an arm extending longitudinally of said body and having one of its ends fixed relative to said body, a cutting tool secured to said arm adjacent its free end, a guide on said body extending parallel to the axis thereof, a guide on said arm extending at an angle to said first mentioned guide, a slide embracing said guides, and means to move said slide to cause the free end of said arm to be drawn toward the axis of said body.
10. A bit comprising a body portion slotted longitudinally from its forward end to form an arm, one end of which is fixed relative to said body, a cutting tool secured to said arm adjacent the free end thereof, a groove in said body extending parallel to the axis thereof, a groove in said arm extending at an angle to said first mentioned arm, a slide in said grooves, a nut carried by said slide, a screw engaging said nut, means for preventing endwise movement of said screw relative to said body and means adapted to be operated in the boring operation of the bit for rotating said screw.
11. A bit for taper boring comprising a body portion having a slit therein forming an arm adapted to carry a tool, the free end of the arm being movable relatively to said body portion, guides on the body and arm, and a slide embracing the guides on the body portion and the arm for positively controlling all movement of the free end of the arm relatively to said body portion.
12. A bit for taper boring comprising a body portion, an arm secured at one end to the body portion and adapted to carry a tool, the free end of the arm being movable relatively to said body portion and resiliently held in a normal position, guides on the body and arm, and a slide embracing the guides on the body portion and the arm automatically operative during the operation of the tool for positively moving said arm inwardly of said normal position toward the axis of relative movement between the tool and work.
13. A bit for taper boring comprising a body portion, an arm secured at one end to the body portion and adapted to carry a tool, the free end of the arm being movable relatively to said body portion, guides on the body and arm, a sliding member embracing the guides on said arm and said body portion whereby sliding movement of said member moves the free end of said arm relatively to said body portion, and means automatically operative during the operation of the tool for imparting sliding movement to said member.
14. A bit for taper boring comprising a body portion, an arm secured at one end to the body portion and adapted to carry a tool, the free end of the arm being movable relatively to said body portion in a direction transverse to the direction of relative movement between the tool and work, guides on the body and arm, a sliding member embracing the guides on said arm and said body portion whereby sliding movement of said member moves the free end of said arm relatively to said body portion, and means actuated by said relative movement for moving said sliding member.

In testimony of which invention, I have hereunto set my hand, at Philadelphia, Pennsylvania, on this 10th day of November, 1924.

JOHN COSTELLO.
